UNITED STATES PATENT OFFICE.

WILLIAM FOREST HENSEL, OF CHICAGO, ILLINOIS, ASSIGNOR TO THE HENSEL AERO STABILIZER COMPANY, OF CHICAGO, ILLINOIS, A CORPORATION OF ILLINOIS.

STABILIZER FOR AERONAUTICAL VEHICLES.

1,112,794.

Specification of Letters Patent.

Patented Oct. 6, 1914.

Application filed August 11, 1913. Serial No. 724,038.

To all whom it may concern:

Be it known that I, WILLIAM FOREST HENSEL, a citizen of the United States, residing at Chicago, in the county of Cook and State of Illinois, have invented certain new and useful Improvements in Stabilizers for Aeronautical Vehicles, of which the following is a specification.

My invention relates to improvements in stabilizers for aeronautical vehicles and has for its general object to provide a stabilizer adapted automatically to operate the balancing devices, such as movable plane members, by which lateral or fore and aft balance is attained in various forms of aeroplanes, hydro-aeroplanes and the like, by positively operating, gravity controlled, appliances.

One of the special objects of my invention is to provide controlling mechanism of positive and certain action, but of such balanced construction as to be delicately responsive to the movements of the gravity responsive parts; and a further object of my invention is to provide construction such that the normal automatic control may be instantly discontinued, to leave the balancing devices subject to such manual controlling appliances as are customarily provided in aeronautical vehicles.

In the drawings, wherein I have illustrated an embodiment of my invention Figure 1 is a front view of an aeroplane equipped with my improved stabilizer for lateral stability; the stabilizer greatly exaggerated in size for clearness of illustration. Fig. 2 is a front elevation of the stabilizer mechanism with parts in sections; Fig. 3 is a vertical section on line 3—3 of Fig. 2 and Fig. 4 is a detail of aeroplane construction taken on line 4—4 of Fig. 1.

The aeroplane structure shown is intended merely to typify any suitable aeronautical vehicle having in its structure movable balancing elements in the form of planes, rudders or wing portions, to be controlled in their movements for maintaining stability. The particular structure shown by way of exemplification consists of the aeroplane 10 having suitable upper and lower planes 11 and 12 and ailerons or balancing planes 13—13' each centrally pivoted as at 14 in a suitable bracket structure 15 to be tilted fore and aft, for securing lateral balance. The front ends of the ailerons 13 and 13' are connected by cables 16 and 16' to opposite

extremities of the power applying piston rod 20, and the rear edges of the said ailerons are connected by cables 17 and 17' to the respectively opposite end of said piston rod 20, (suitable pulleys being of course provided to direct the cables) so that movement of the piston rod 20 in the direction of either aileron produces an elevation of the rear edge of that aileron and an elevation of the front edge of the opposing one.

As far as the automatic devices herein-after described are concerned, the piston rod 20 constitutes a part to be moved for control of the balancing operation. It carries a central piston 21 contained in a double ended cylinder 22 whereof 23 and 23' represent the opposite chambers each of which has a port, 24 and 24' respectively, which may act both as the intake and exhaust port for the fluid to move the piston.

The apparatus controlling the introduction of operating fluid into the two ends of the cylinder provides substantially all of its parts in duplicate, and is symmetrically arranged, so that as I describe the appliances appurtenant to one chamber of the cylinder it is to be understood that they are duplicated with respect to the other chamber and identified by the same number, primed (').

Port 21 has piping connection 25 with an intake valve 26 controlling the supply of fluid from a pressure pipe 27. Said port 24 also has piping connection 28 to an exhaust valve 29 having its outlet opening 90 into the air, said exhaust valve 29, for convenience of the operation hereafter described, being preferably located immediately below the supply valve 26' for the opposite chamber of the cylinder, for the general purpose of causing operating parts, moving in one direction, simultaneously to open the intake valve for one chamber of the cylinder and to close the exhaust valve for said chamber. Each intake valve, 26 and 26', preferably comprises a shell 26^a divided by valve seat 26^b into two chambers respectively connected with pipes 25 and 27, communication therebetween being controlled by the valve-proper 30 pressed by a spring 31 toward closed position, the valve stem extending inwardly through a spring-pressed packing-gland 26^c and bearing on its extremity an adjustable contact head 32. The exhaust valve 29' for the opposite side

of the cylinder is secured directly below valve 26, and said exhaust valve comprises a shell 29^a divided by valve seat 29^b into two chambers, one of which has ports 29^c 5 to the atmosphere and the other of which connects with the exhaust pipe 28'. Valve proper 35, controlling communication between the two valve chambers, is carried by a stem 36' which extends through both ends 10 of the casing.

For gravity control of the power valve operation I provide a tube 40 closed at each end, preferably inclined downward in both directions from a central crest and forming 15 oppositely inclined run ways for two balls of gravity-responsive devices 41 and 41'. For coöperation with the two balls I provide suitable lever-means, a central lever 42 being pivoted to the cylinder 22 and extending 20 downward between and in contact with the contact heads 32 for the valves 26 and 26' and through an opening 43 at the crest or center of the double inclined tube 40, so that in addition to operating the supply valves it 25 retains each ball in its own half of the tube 40. This lever 42 also has balanced spring connections by light springs 44 and 44' to the stems of exhaust valves 29 and 29' respectively so that as the lever 42 is thrown 30 to the left, say, the tension on spring 44, tending to close valve 29 for chamber 23 is increased. Other levers 45 and 45' depending from pivotal supports on the cylinder 22 extend through apertures 46 and 46' near 35 the ends of casing 40 normally to receive in contact therewith the balls 41 and 41'. Each such lever has a link connection, 47 and 47', respectively with the outer extremity of the valve rod for the contiguous exhaust valve 40 29 or 29' for positively exerting an opening 45 action thereon, the weight of balls 41, 41' normally overcoming springs 44, 44' and holding both relief valves open. This arrangement, in lieu of direct connection of the 50 valves 29, 29' to be pulled closed by lever 42, facilitates, as a matter of refinement, but of practical advantage, the normal maintenance of both relief valves in open position and the provision made for instantaneous re- 55 lief of the balancing mechanism from automatic control so that manual control of the balancing function may be assumed. Such provision diagrammatically shown in the drawings, may be made, for example, by 60 equipping the supply pipe 127 which supplies compressed air or other operating fluid to the pipes 27 and 27', with a rotary cut off valve 50 provided with a handle 51, shown in open position in Fig. 2 and which is 65 turned down to vertical position to cut off the fluid supply. The valve handle 51 may operate a cord 53 which has connection over suitable pulleys with two spring pressed 70 plungers 54 and 54' mounted on the tube 40 75 and so arranged that when the valve 51 is

turned to lowest position so as to cut off the supply of operating fluid from the intake valves 26 and 26' the slackening of cord 53 permits both plungers 54 and 54' to press outwardly, throwing outwardly in opposite 70 directions the two levers 45 and 45' thereby to open both outlet valves 29 and 29' simultaneously with the cutting off of the fluid supply, regardless of the positions of balls 41, 41' and lever 42. Any suitable manual 75 controller for the ailerons, such, for example as hand lever 56, operatively connected with the part to be moved, or piston rod, 20, may then have unimpeded control of the balancing planes. 80

The parts described control lateral balance only, the ball runway being arranged transversely of the aeroplane, but a duplicate installation, with the ball-runways arranged fore and aft, may be provided to control the horizontal tail-rudder, front elevator, or other parts employed for securing fore and aft balance. This duplication is not shown as it would involve only confusing multiplication of parts in the drawing. 90

In operation it will be understood that opposite tilting of the ailerons 13 and 13' tends to raise one side of the aeroplane and depress the other. When the machine tilts, with its left hand side (Fig. 1) raised, until the center of the tube 40 is lower than its left end, ball 41 rolls down against lever 42, throwing the latter to the right, closing relief valve 29' and opening inlet valve 26', while relief valve 29 of course remains open. This introduces compressed air from pipe 127 into cylinder chamber 23', the piston 21 moves to the left, the front edge of the right hand aileron is raised and the other aileron correspondingly lowered. As a result, obviously, 95 balance is restored. When the vehicle resumes nearly balanced position ball 41 rolls back against lever 45', opening relief valve 29' and permitting the spring pressed pressure valve 26' to close, so that, both relief 100 valves being opened, the air pressure on the ailerons (or spring pressure used in some aeroplanes) may move them, or they may be hand moved, back to normal position. 105

Manifestly when valve handle 51 is turned 115 down cutting off the compressed air supply and permitting plungers 54, 54' to press back both levers 45, 45', the piston 21 may travel freely and manual control of the balancing devices may be wholly relied on. 120

While I have herein described a particular embodiment of my invention for full disclosure, it will be apparent that changes may be made in its details without departure from the spirit of my invention and within 125 the scope of the appended claims.

Having described my invention, what I claim is:

1. The combination with an aeronautical vehicle having movable balancing plane por- 130

- tions, of means to automatically operate said balancing portions comprising a piston rod operatively connected with said balancing portions, a piston thereon, a cylinder for said piston, supply and exhaust valves for each chamber of said cylinder, and two independent gravity responsive means operable in response to tilting of the vehicle in either direction, each of said gravity responsive means operating the supply valve of one chamber and exhaust valve of the other chamber to cause piston movement in an appropriate direction.
2. In a balancing means for aeronautical vehicles having movable balancing plane parts, means to automatically operate said balancing parts comprising a piston rod for connection with said parts, a piston thereon, a cylinder for said piston, an intake valve and an exhaust valve for each chamber of the cylinder, the intake valves normally closed and the exhaust valves normally open, two oppositely inclined runways, gravity responsive movable parts in said runways, and operating connections, mechanically operable by pressure of said gravity responsive parts for opening the supply valve and closing the exhaust valve of the appropriate chamber in response to tilting of the vehicle.
3. In a balancing means for an aeronautical vehicle having movable balancing wing parts, means to automatically operate said wing parts, comprising a power cylinder, a piston therein, a piston rod operatively connected with the wing parts, a tube providing oppositely inclined runways, two balls in said runways respectively, a supply valve and exhaust valve for each chamber of the cylinder, and lever means actuated by the balls for opening either supply valve and closing the corresponding exhaust valve extending into said runway for operation by the balls.
4. In a device of the character described, the combination with the double ended cylinder containing a piston and a connected part to be moved, an operating lever, supply valves for opposite ends of the cylinder, disposed at opposite sides of said lever for operation thereby, and normally open exhaust valves for opposite ends of the cylinder disposed on the sides of said lever opposite to the supply valves for the same chambers of the cylinder, controlled for closure by said lever, oppositely inclined runways associated with said lever, and gravity responsive means in said runways alternatively movable to operate said lever accordingly as the vehicle is tilted in one direction or the other.
5. In a device of the character described, the combination with the double ended cylinder containing a piston and a connected part to be moved, an operating lever, supply valves for opposite ends of the cylinder, disposed at opposite sides of said lever for operation thereby, an exhaust valve for each end of the cylinder disposed on the side of said lever opposite to the supply valve for the same chamber of the cylinder, said exhaust valves spring connected to said lever, oppositely inclined runways associated with said lever, and gravity responsive means in said runways alternatively movable to operate said lever accordingly as the vehicle is tilted in one direction or the other.
6. In a device of the character described, the combination with a part to be moved, a piston and cylinder, of exhaust and supply valve means for each end of said cylinder, automatic gravity controlled means for simultaneously opening the intake valve and closing the exhaust valve for one cylinder chamber, and manually controlled means for simultaneously locking both exhaust valves for the two chambers of the cylinder in open position and cutting off the fluid supply for both chambers irrespective of the gravity controlled means.
7. In a device of the character described, a cylinder, a piston therein, a piston rod to be moved, normally closed intake valves for both chambers of the cylinder, lever means common to said valves for alternatively opening the same, exhaust valves for the respective cylinder-chambers, individual lever means for opening the same, a double-inclined runway, and two balls therein, each ball operatively associated with the common lever means for the two intake valves and with the individual lever means for one exhaust valve.
8. In a device of the character described, a double-inclined runway having a central crest, gravity responsive means in each end of the runway, a central movable part extending into the runway for opposite operation by the respective gravity responsive means, opposed movable parts in opposite ends of the runway for movement by the respective gravity responsive means, a cylinder, a piston therein, and intake controlling means and exhaust controlling means for each chamber of the cylinder, the intake controlling means for both chambers operated by said central movable part, and the exhaust controlling means for each chamber operated by the opposed movable parts.
- In testimony whereof I hereunto set my hand in the presence of two witnesses.

WILLIAM FOREST HENSEL.
